AUTOMATICALLY OPERATED ADDING MACHINE

Kenneth A. Milette, La Puente, and Robert K. Fujioka,
Los Angeles, Calif., assignors to Datex Corporation,
Monrovia, Calif., a corporation of California

Filed Jan 7, 1959, Ser. No. 54,069

Term of patent 14 years
(Cl. D64—11)

Fig. 1.

Fig. 2.

Fig. 1 is a front perspective view of an automatically operated adding machine showing our new design, the back thereof being conventional; and

Fig. 2 is a side elevational view thereof as seen from the right of Fig. 1.

The essential features of the design reside in the portions shown in solid lines on the drawing.

We claim:

The ornamental design for an automatically operated adding machine, as shown and described.
